Primary Examiner—Raphael Barkai*Attorney, Agent, or Firm*—Baker Botts L.L.P.[57] **CLAIM**

The ornamental design of a compact of the present invention, as shown and described.

DESCRIPTION

FIG. 1 is a three-dimensional perspective view of the compact of the present invention;

FIG. 2 is a top view of the compact of the present invention;

FIG. 3 is a side view of the compact of the present invention;

FIG. 4 is a front view of the compact of the present invention;

FIG. 5 is a back view of the compact of the present invention; and,

FIG. 6 is a bottom view of the compact of the present invention.
